RUFFLING MECHANISM FOR SEWING-MACHINES.

No. 841,546.

Specification of Letters Patent.

Patented Jan. 15, 1907.

Application filed June 28, 1905. Serial No. 267,373.

To all whom it may concern:

Be it known that I, ALEXANDER LAUBSCHER, a citizen of the United States, residing at Bridgeport, in the county of Fairfield and State of Connecticut, have invented a certain new and useful Improvement in Ruffling Mechanisms for Sewing-Machines, of which the following is a full, clear, and exact description.

This invention relates to ruffling mechanisms for sewing-machines; and its object is to provide a machine in which the ruffling mechanism is automatically controlled as to the time and extent of its operation independently of the operation of the stitch-forming and cloth-feeding mechanisms.

The invention comprises mechanism automatically operated from some driven part of the sewing-machine, such as the needle-actuating shaft, whereby the movements of a crimping-blade are controlled both as to time and extent so as to insert in a seam at any desired point or points a number of plaits or gathers. The crimping-blade is mounted so as to receive the ordinary vibrating or reciprocating movements, and without stopping its actuating mechanism the latter is rendered alternately effective and ineffective by the automatic controlling mechanism first mentioned, as will now be described and finally claimed.

In the accompanying drawings, illustrating the invention, in the several figures of which like parts are similarly designated, Figure 1 is a front side elevation with the bed-plate and overhanging arm in part in section. Fig. 2 is a rear side elevation. Fig. 3 is a bottom plan view. Fig. 4 is a vertical section, on a larger scale, taken on the line A B, Fig. 1. Fig. 5 is a sectional elevation in the plane of line C D, Fig. 1, looking toward the right. Fig. 6 is a sectional elevation in the plane of line E F, Fig. 1, looking toward the left. Fig. 7 is a plan view below the plane of line G H, Fig. 9. Fig. 8 is a perspective view of the device for holding the work as the crimping-blade retracts. Fig. 9 is a front end elevation of a portion of the machine, showing a part of the ruffling mechanism adjusted to its operative position. Fig. 10 is a longitudinal section showing a detail of the automatically-controlled connection for transmitting movements to the crimping-blade.

Fig. 11 is a perspective view illustrating one form of the work.

55

1 indicates the usual bed-plate; 2, the overhanging arm; 3, the needle-actuating shaft, suitably mounted in the overhanging arm; 4, the band-wheel; 5, the needle-bar, adapted in any usual way to be operated from the needle-shaft.

6 is the take-up lever; 7, the presser-bar, provided with the usual tension-spring. (Not shown.)

8 is the presser-bar lifter; 9, the presser-bar-lifter collar; 10, the presser-bar adjustable bearing.

11 and 12 are the thread-checks.

13 is the thread tension.

14 is the thread-controller; 15, the thread-leader; 16, the face-plate.

17 is a rod secured by screw 18 in suitable bearings in the overhanging arm and provided with a slot (see dotted lines, Fig. 2) into which an arm 19 of the presser-bar-lifter 75 collar 9 projects to prevent radial movements of the presser-bar.

20 is the take-up-lever screw; 21, the lower main shaft.

22 represents quartering crank connections for transmitting motion from the needle-actuating shaft 3 to the lower main shaft.

23 is the auxiliary hook-shaft; 24, the driving-gear, carried by the lower main shaft and meshing with a driven gear 25, carried by 85 the auxiliary hook-shaft 23, such gears being of the ratio of two to one, thus giving to the auxiliary hook-shaft two revolutions to one revolution of the needle-actuating shaft 3.

26 represents bevel-gears mounted upon 90 the auxiliary hook-shaft 23 and meshing with bevel-gears 27, secured to the lower end of the loop-taker shaft (not shown) for transmitting rotary movements to the loop-takers 28.

95
29 represents brackets adjustably secured by screws 30 to the under side of the bed-plate and provided with suitable bearings in which the loop-taker shafts are mounted.

31 is the feed-adjusting lever secured to the outer end of the rock-shaft 32 and provided with an adjustable stop 33, the rock-shaft 32 being provided with a lever 34, pivotally connected by a link 35 to an adjusting-lever 36, which is pivotally attached to an arm 37 of 105 the feed rock-shaft 38, the opposite end of

the lever 36 being provided with a slide-block 39, adjustably secured to a flange 40 on a rock-lever 41, which latter is provided with a shaft 42, mounted in suitable bearings 43 on the bed-plate.

44 is an eccentric secured to the lower main shaft 21, which coacts with the forked end 45 of the lever 41 to give, through the connections 36, 37, and 39, rocking movements to the feed rock-shaft 38. To the forward end of the feed rock-shaft 38 is secured a lever 46, to the outer end of which is pivotally connected a feed-bar 47, carrying a feed-dog 48 and given longitudinal movements through parts 36, 38, 41, 44, 46, and 47. The end of the feed-bar 47 opposite to that attached to the lever 46 has a groove (not shown) in which works a slide-block 49, mounted on a stud 50, secured in the outer end of an arm 51 on the lift rock-shaft 52, mounted between pindle-bearings 53. To the end of the lift rock-shaft 52 opposite to that provided with the arm 51 is secured a forked lever 54, acted upon by an eccentric 55, carried by the lower main shaft 21 for giving, through the connections 49, 50, 51, and 52, vertical movements to the feed-bar 47.

56, Figs. 2, 5, and 6, is a horizontal rock-shaft mounted in a bearing 57, formed at the rear side of the bracket 58, and 59 is a lever fast on the end of said rock-shaft and connected by a pitman 60 with an eccentric 61, Figs. 1, 5, and 6, secured on the needle-actuating shaft. The lower end of this pitman is pivoted to said lever by a stud 62 and its upper end is strapped around said eccentric in any usual manner.

63 is a horizontal rock-shaft mounted in a bearing 64 at the front of the bracket 58, said rock-shaft carrying at one end a lever 65, which has adjustably secured to it an extension-lever 66, which carries at its lower end a pivotally-secured bracket 67, to which latter is secured the crimping-blade 68. The pivoted bracket 67 is provided with an arm 69, which when the presser-bar is raised is acted upon by an arm 70 to tilt the forward end of the crimping-blade upward, the said arm 70 being secured in a bracket-collar 71, attached to the presser-bar. The extension-lever 66 is provided with a stud 72, which has riveted to it a rod 73, which passes through an eye 74, formed integral with the pivoted bracket 67, the rod 73 being provided with a spring 75 and an adjusting-nut 76, one end of the spring acting against the inner side of the adjusting-nut and its opposite end resting against the outer side of the eye 74, thus causing the spring 75 to hold the free end of the crimping-blade down upon the material.

To the end of the rock-shaft 63 opposite to that upon which the lever 65 is mounted is secured a lever 77, which extends alongside the lever 59, with which it is coupled by ad-

justably-secured slide-blocks 78 and 79, Fig. 10, loosely mounted upon a stud 80, secured by a nut 81 in the end 82 of a link 83, the other end of which is secured by a screw 84 to the lower end of a lever 85, depending from a shaft 86, mounted in suitable pindle-bearings 87, the shaft 86 being provided with a coiled spring 88, which is set to hold, when free to act, the blocks 78 and 79 at the axis of the shaft 56. Through the action of the lever 85 the slide-blocks 78 and 79 are adjusted in the groove 89, formed in the lever 77, and groove 90, formed in the lever 59, so that movements of greater or less extent may be given the crimping-blade 68, and by adjusting the blocks 78 and 79 through the resiliency of spring 88 at the axis of the shaft 56 the movements of the crimping-blade are automatically suspended independently of the operation of the stitch-forming mechanism.

The stitch-forming, cloth-feeding, and ruffling mechanisms thus far described are of the usual construction; but others having essentially the same or even like capabilities may be used instead.

The parts more directly involved in the present invention are as follows:

91 is a cam-shaft having one end 92 seated in a bearing 93 in the upright portion 94 of the arm and its opposite end 95 passed through the hub 96 of a worm-gear 97, which hub rotates in a bearing 98 in said portion 94, and the shaft 91 is capable of longitudinal movement. Secured on the end 95 of the shaft 91 is a cam-disk 99, provided with a cam portion 100, the cam-disk 99 being held against accidental movement on the shaft 91 by being threaded upon said shaft and fixed with a set-screw 101. Upon the end 92 of the shaft 91 is secured by a screw 102 a dial 103, formed with a knurled knob 104. Mounted upon said shaft between the bearing 93 and hub 96 is a spring 105, normally held compressed against the end of the hub 96 by a collar 106, which is secured to said shaft by a screw 107, thus normally forcing the shaft 91 and its attached parts in the direction indicated by the arrow s. The cam-disk 99 carries a pin 108, which coacts with holes 109 in the worm-gear 97, distributed equidistant from each other and from the axis of said worm-gear, so that when the pin is interlocked with one of the holes by the normal expansive action of the spring 105 the cam-disk 110 is caused to rotate synchronously with the worm-gear 97. The upright is provided with a raised portion 110, surrounding the periphery of the dial 103, and provided with a pointer 111, secured by screw 112. The graduations on dial 103 are numbered in sequence in a direction opposite to that of the dial's rotation, and said dial is held normally away from its seat 113 sufficiently to permit the shaft 91 and its attached parts 130

to be manually moved in a direction opposite to that indicated by the arrow *s* to release the pin 108 from one of its coacting holes 109, thus enabling the operator to reset 5 the cam portion 100 relatively to the worm-gear 97. Upon the opposite side of the upright portion 94 is a seat 114, on which is seated a bracket 115, secured by a screw 116. The bracket 115 is constructed with bearings 10 117 118, in which is mounted the worm-gear shaft 119, which has mounted upon it a sleeve 120, secured in position by screws 121 and provided with a worm 122, which meshes with the teeth 123 of the worm-gear 97. On 15 one end of the shaft 119 is secured by screws 124 a gear-wheel 125, which meshes with a smaller gear-wheel 126, fast on the needle-actuating shaft 3, such gears preferably being of the ratio of four to one; but any other 20 desired proportion may be used. The gear-wheel 126 acts through the connections 122, 125, 119, 120, and 123 to transmit rotary movements to the worm-gear 97. In the bracket 115 is formed a third bearing 127, in 25 which is mounted the shaft 128 of a lever 129; said shaft having secured to it by screws 130 a lever 131, which carries a roller 132, which coacts with the cam portion 100 of the cam-disk 99 when such cam portion is caused to 30 rotate in the path of said roller. The lever 129 has formed in it a groove 133, in which is movably secured a slide-block 134, held against accidental displacement by a stud-bolt 135, secured in a slot 136, formed in the 35 lever 137, the stud-bolt 135 being adjustably secured by the tightening of the thumb-nut 138. The lever 137 is secured by a set-screw 139 upon the rock-shaft 86.

140 is a base-plate adjustably secured by 40 screw 141 to the bed-plate 1. Upon this base-plate is adjustably secured by screws 142 (see Fig. 7) a folder-plate 143 and by screws 144 a folder-plate 145. The folder-plate 145 is provided with a scroll-guide 146, 45 a guide-slot 147, and a crimping-plate 148, the latter preferably integral with the folder-plate 145, and the folder-plate 143 is provided with a scroll-guide 149. The crimping-plate 148 cooperates passively with the crimping-plate 148 in the formation of the plaits or 50 gathers, said crimping-blade being arranged over the crimping-plate. The bed-plate 1 has a depression to accommodate the thickness of the base-plate 140, so that the crimping-plate 148 will occupy a position above 55 the throat-plate 151 sufficient only to accommodate the highest lift of the feed-dog 48. The throat-plate 151 forward of the needle has a like elevation, the remaining portion 60 being on the same plane as the front and back slide-plates 152 and 153, respectively.

To the lower end of the presser-bar 7 is secured by screw 154 a bracket 155, provided with a pivotally-mounted cloth-presser 156 65 of approved construction, which coacts with

the feed-dog 48 to intermittently advance the material to the action of the needle 157. The bracket 155 is provided also at one side with an offset portion or lug 158, to which is secured by screw 159 a bracket 160, provided 70 with a spring-plate 161, which at its free end is turned downward and there provided with notches or teeth 162, the spring-plate 161 being secured to the bracket 160 by a screw 163. The object of the toothed spring-plate 161 is 75 to prevent the folds or plaits formed by the crimping-blade from following the return movements of such blade, as the teeth 162 act directly upon the upper surface of the material as it is fed below the crimping-blade and 80 over the crimping-plate.

The operation is as follows: Assuming that a man's dress-shirt is being made and that the material 164, Fig. 11, comprising the body portion is to be joined to the yoke 165. 85 by seaming the several parts together in such manner that the material 164 is plaited or gathered between and at some distance from the ends of the seams 166 and that the graduated disk 103 is adjusted so that the pointer 90 111 registers at 12 on the dial, which would place the cam portion 100 in a position opposite to that indicated in Fig. 4 or intermediate its operative position relatively to the roller 132, and it also being assumed that the 95 edge 167 of the material 168 is in the scroll-guide 149, the edge 169 of the material 170 in the scroll-guide 146, and the edge 171 of the material 164 in the guide-slot 147, then the machine being put into operation the several plies of the material will be fed to the 100 action of the needles and a plain two-needle seam be formed from 172 to 173, during which time the cam portion 100 will be rotated in the direction indicated by the arrow 105 to contact with the roller 132, and as the roller mounts the incline of the cam portion 100 the shaft 86 through the connections 129 to 137, inclusive, will be rocked in opposition to the resiliency of the spring 88, thus moving the lever 85 and its attached slide-blocks 110 gradually away from the axis of rock-shaft 56 to the position which will give to the crimping-blade its greatest throw. Then the roller 132 will ride the incline on the opposite side of the cam portion 100 and the spring 87 will gradually return the shaft 86 to its normal position, causing the lever 85 and its attached slide-block to be again adjusted 115 central with the axis of the rock-shaft 56, thus 120 forming the plaits in the seam from 173 to 174, followed by the formation of the regular two-needle seam from 174 to 175 or to the finish of the seam.

It is evident that one or more seams may be 125 formed. If the production were substantially as herein pointed out, the stitching would be started with the graduated disk 103 adjusted relatively to the pointer 111 at 12 on the dial, the formation of the plaits would 130

commence substantially equidistant between dial-points 5 and 6 and terminate substantially equidistant between dial-points 6 and 7, when the plain two-needle stitching would be 5 continued to the end of the seam.

It is to be understood that many adjustments are provided so as to meet many kinds of work without necessitating the readjusting of the dial relatively to the pointer, as, for instance, if the length of the stitch were diminished or increased the length of the seams over all would be proportionately lengthened or shortened and the plaits or gathers would be nearer together or farther apart, thus distributing them over a greater or less portion 15 of the seam, and if the adjustable connection comprising the parts 134 135 were adjusted nearer to or farther from the axis of the rock-shaft 128 the plaits would be formed proportionately wider or narrower; but if the production required the placing of the plaits out 20 of central relation to the opposite ends of the seam then the operator before starting the machine would reset the cam-disk 99 to such 25 position as would properly locate the plaits relatively to the length of the seam.

It is evident that the scroll-guide might be dispensed with and a crimping-plate, such as is commonly used in connection with the ordinary ruffling mechanism, substituted for it and ruffles formed at predetermined intervals.

While the invention is shown specialized for shirt-making, it is to be understood that 35 it is adaptable for other special work and also for general manufacturing purposes. Further, it is to be understood that while the power for operating the mechanism is most conveniently taken from the needle-actuating 40 shaft still obviously the power may be derived elsewhere, as from a separate shaft, and in the claims herein made the mention of the needle-actuating shaft is more by way of illustration of a power source than a limitation 45 of the invention.

What I claim is—

1. In a ruffling mechanism for sewing-machines, a stitch-forming mechanism, a cloth-feeding mechanism, a crimping-blade, means 50 for operating the same and means for controlling said operating means, including a cam-disk provided with a cam portion, means to rotate said cam-disk, and means for connecting said cam-disk with and disconnecting 55 it from its rotating means, for automatically controlling the action and inaction of the crimping-blade for forming a cluster of plaits or gathers at a predetermined point in the line of seam.

60 2. In a ruffling mechanism for sewing-machines, a stitch-forming mechanism, a cloth-feeding mechanism, a crimping-blade, means for operating the same and means for controlling said operating means, including a rotary cam, a shaft on which the cam is fixed

and by which it may be adjusted manually and independently of the means for operating the crimping-blade to automatically determine the position of the plaits in the line of the seam.

70

3. In a sewing-machine, a stitch-forming and a cloth-feeding mechanism, a crimping-blade and connections between said stitch-forming mechanism and the crimping-blade for operating the same, and controlling means 75 including a dial and an adjustably-mounted rotary cam connected with said dial for automatically controlling the action and inaction of the crimping-blade.

4. In a ruffling mechanism for sewing-machines, a stitch-forming mechanism, a cloth-feeding mechanism, a crimping-blade, means for operating the same and means for controlling said operating means, including a cam, means to rotate it and independent 80 means for adjusting the cam relatively to its rotating means, the cam-adjusting mechanism being operable independently of the sewing elements to reset the cam for each new seam and thereby insure the proper location 85 of the plaits or gathers.

5. In a sewing-machine, a needle-actuating shaft, and a dial, an adjustably-mounted cam with which said dial is connected, said cam carried by a disk, gearing connecting 95 said disk and shaft, a crimping-blade, and means including an eccentric and an eccentric-strap for connecting said blade with the needle-actuating shaft, in combination with a 100 slidable connection automatically controlled by said adjustably-mounted cam to effect or suspend the action of the crimping-blade at predetermined intervals.

6. The combination of stitch-forming and cloth-feeding mechanisms including a driving-shaft, a crimping-blade, means to drive it from said shaft including levers coupled by a shiftable coupling, a lever connected to said coupling, a spring-held rock-shaft on which said lever is fixed and means connected 110 with the driving-shaft for positively rocking the rock-shaft periodically.

7. The combination of stitch-forming and cloth-feeding mechanisms including a driving-shaft, a crimping-blade, means to drive it from said shaft including levers coupled by a shiftable coupling, a lever connected to said coupling, a spring-held rock-shaft on which said lever is fixed, means connected with the driving-shaft for positively rocking the rock-shaft periodically, and means for varying the extent of the rocking movement.

8. The combination of stitch-forming and cloth-feeding mechanisms including a driving-shaft, a crimping-blade, means to actuate 125 said blade from said shaft including crossed rock-levers having a shiftable coupling, and means for periodically suspending the movement of the blade while the driving-shaft is operating, same comprising a rock-shaft, a 130

lever thereon connected with the shiftable coupling, means to actuate the rock-shaft from the driving-shaft, and means to control the actuation of the rock-shaft including a cam, a spring-held adjustable shaft on which it is mounted, and worm-gearing with which said cam is adapted to be connected at the will of the operator.

9. The combination of stitch-forming and cloth-feeding mechanisms including a driving-shaft, a crimping-blade, means to actuate said blade from said shaft including crossed rock-levers having a shiftable coupling, and means for periodically suspending the movement of the blade while the driving-shaft is operating, same comprising a rock-shaft, a lever thereon connected with the shiftable coupling a parallel rock-shaft, connecting-levers on said rock-shafts having an adjustable connection, a cam, a cam-arm on the parallel rock-shaft coöperating with the cam, gearing connecting the cam with the driving-shaft, and means to connect and disconnect the cam and gearing.

25 10. In a ruffling mechanism for sewing-machines, a stitch-forming mechanism, a cloth-feeding mechanism, a crimping-blade, means for operating the same and means for controlling said operating means, including a cam having two independently-operating rotating mediums whereby the cam is respectively rotated with the sewing elements and at pleasure rotarily adjusted with relation to its first-mentioned rotation to reset the cam 30 for each new seam and thereby insure the proper location of the plaits or gathers.

35 11. In a sewing-machine, a stitch-forming mechanism and a cloth-feeding mechanism, a crimping-blade and connections between

said stitch-forming mechanism and the 40 crimping-blade whereby the width or fullness of the plaits or gathers is gradually increased as the crimping-blade is brought into action and gradually decreased as the crimping-blade is thrown out of action, and including 45 means for automatically controlling the operation of the crimping-blade to determine the location of the plaits in the seam.

12. In a sewing-machine, a stitch-forming mechanism and a cloth-feeding mechanism, 50 a crimping-blade and connections between said stitch-forming mechanism and the crimping-blade for operating the crimping-blade, and for determining the time of action and inaction of the crimping-blade, and the 55 location of the plaits or gathers in the seam, said connections including a cam, means for rotating the same in one direction, means for maintaining said cam coupled with its rotating means throughout a complete rotation, and resetting devices for said cam.

13. In a sewing-machine, a stitch-forming mechanism including a needle-actuating shaft, a cloth-feeding mechanism, a crimping-blade and connections between it and the 65 needle-actuating shaft for operating the crimping-blade and varying its throw to form a bunch of plaits or gathers of varying width or fullness and for controlling the time of operation of the crimping-blade, said 70 connections including a rotary cam and adjusting devices therefor.

In testimony whereof I have hereunto set my hand this 20th day of June, A. D. 1905.

ALEXANDER LAUBSCHER.
